IMPLEMENT FOR COLLAPSING HOLLOW
RIVETS

Edgar Hiler, Grand Prairie, Tex.

Application November 6, 1946, Serial No. 707,999

3 Claims. (Cl. 218—19)

1

This invention relates to machines for installing blind rivets and it has particular reference to a machine for installing and collapsing hollow, internally threaded rivets.

The principal object of the invention is to provide a manually manipulated but automatically operated machine having and exteriorly threaded and interchangeable applicator head or mandrel of case hardened material, said machine further having means for rotating the mandrel into a hollow rivet preparatory to installing the latter in a hole drilled in the work, combined with means for retracting the mandrel to impose a collapsing force on the rivet intermediate its ends to permanently bind the work parts together, said mandrel rotating means being reversible to release the mandrel from the collapsed rivet.

Another object of the invention is to provide a machine for quickly and efficiently installing hollow rivets in blind or inaccessible places, consisting of a reciprocal squeezing unit and a reversible rotary unit in fixed parallelism to actuate a mandrel each being pneumatically operated but independently controlled for installing and collapsing a rivet in the permanent joining of work pieces and for withdrawing the mandrel from the fixed rivet. Moreover, provision is made to effect adjustment in the stroke length of the reciprocal squeezing unit to adopt the same to rivets of various lengths.

With the foregoing and other objects in view, the invention has particular reference to certain features of accomplishment, to become manifest as the description proceeds taken in connection with the accompanying drawing wherein:

Figure 1 is a longitudinal sectional view of a tool constructed according to the invention.

Figure 2 is a top plan view of that part of the tool forwardly of and omitting the motivating units, and

Figure 3 is a vertical sectional view taken on line 3—3 on Figure 1.

Continuing with a more detailed description of the drawing, reference numeral 10 denotes generally the head or forepart of the rivet installing machine which is affixed, by means of bolts 11 to a plate 12, the latter, in turn, extending from the head of conventional squeezing tool. No claim is made herein to the squeezing tool structurally but rather to its function on that of equivalent

2

means for exerting a collapsing force on a rivet in a manner to be presently described.

The squeezing tool, as shown, consists of a cylinder 13 in which operates a piston 14, the latter carrying a cam plate 15. The cylinder 13 merges into a body 16, from which the head mounting plate 12 extends and to which latter, as stated, is attached the head 10 of the rivet installing machine. It is the purpose of the squeeze tool to reciprocate a plunger 17 for a purpose to be presently made clear. The plunger 17 is reciprocally mounted in a bushing 18 in the head and is provided itself with a head 19 against which bears a compression spring 20, the opposite end of the spring bearing against an end of the bushing 18 to normally urge the plunger in a rearwardly direction. With the plunger 17 in retracted position, a link 21, shown in axial alignment with and abutting the head of the plunger, will be disposed in an angular plane in relation thereto so that its roller 22 will bear against the cam surface 23 of the cam plate 15 with the latter retracted. When air is admitted into cylinder 13 by opening a valve 24, piston 14 therein is advanced, urging the cam plate 15 in a forwardly direction to exert a force on the link 21 which will be displaced in such manner as to impose an axial thrust upon the plunger 17 against the resistance of spring 20. Since the squeeze tool is of conventional construction, a detailed explanation of its composition and function is not considered necessary as these are well within the knowledge of those skilled in the art.

Affixed to the squeeze tool body 16 and cooperating therewith in a manner to be presently explained, is a reversible rotary unit which, in the present case consists of a conventional pneumatic screw driving machine. This unit is comprised of a housing 25 containing an air motor, which is not shown in view of its well known construction, but which imparts rotation to a shaft 26 emerging from the forward end of the housing 25. An air inlet tube 27 enters the housing at its rear end to operate the motor in the housing.

45 A lever 28 is mounted on the housing 25 for the purpose of actuating a valve 29 to introduce air into the casing 25 for driving the motor therein which normally revolves shaft 26 in a clockwise direction. To reverse the direction of rotation 50 of the shaft 26, a lever 30 is located on the side

of the housing 25. The screw driving machine adapted in the manner described, being of standard construction, has not been illustrated in detail since its construction, assembly and function are well known.

Referring now specifically to the actual rivet installing mandrel and the relationship therewith of the rotary and reciprocating units described, it will be observed in Figures 1 and 2 that the head 10 is disposed at a slight angle in relation to the longitudinal axis of the tool as a whole and is formed with a boss 31 having an axial bore through which extends the mandrel 32. This mandrel consists of a case hardened shaft whose outer end is threaded at 33 and on its opposite end is formed a head 34.

A slideable carriage 35 is mounted on the head 10 having an unstanding leg 36 at right angles to the body thereof, in which is formed a cavity 37 receiving the head 34 of the mandrel 32. An undercut groove 38 is formed in the inclined upper surface of the head 10 to receive the flanged base of the carriage 35 and holds the latter against other than reciprocative displacement on the head. Bearing against the rear end of the carriage 35 is a coiled spring 39, normally urging the carriage in a forwardly direction to exert a forward thrust on the mandrel 32, by virtue of a pinion 40, affixed to the mandrel and lying in an oblong recess 41 (Fig. 3) in the facial portion of the carriage leg 36. A plate 42 overlies the spring 39 enclosing the same against dust and foreign matter.

Disposed also in the oblong recess 41 is a pinion 42 of analogous diameter to and enmeshing pinion 40. This pinion 42 is mounted on the end of a shaft 43, spaced from but disposed parallel to the inclined upper surface of the head 10. The upper end of shaft 43 is slidably retained in a sleeve 44 by means of a pin 45 on the shaft which enters a longitudinal slot 46 in the sleeve. The sleeve 44 is a part of a universal joint consisting of the sleeve and a complementary sleeve 47, mounted on the end of the shaft 26 of the air motor contained in the housing 25 of the rotary unit.

In order that the mandrel 32 may be reciprocated, this motion is applied to the carriage 35 by means of a lever 48 which is pivoted in a cavity 49 in the head 10 by means of a transverse pin 50. The upper end of the lever operates in a recess 51 in the underside of the carriage 35 and its opposite end is engaged by the protruding end of the plunger 17 of the squeeze tool earlier described. Thus it will be seen that as 55 the plunger 17 is advanced against the lower and rounded end 52 of the lever 48, the latter will be rocked on its pivot and will move the carriage 35 rearwardly against the resistance of spring 39, thereby retracting the mandrel 32 to accomplish the function to be presently explained.

The type of rivet adapted to be installed by the described invention is shown in longitudinal section in Figure 1 as securing together juxtaposed work pieces 53 and it will be assumed that the side of the work assembly opposite the tool is inaccessible or "blind." The rivet 54, consists of a hollow, cylindrical body, interiorly threaded a predetermined depth opposite its head 55 which may be convex as shown, or other shapes. The boss 31 of the head 10 has a recess 56 of a shape corresponding to the type of head on the rivet so that the head will lie wholly or partly in the recess.

To fasten the rivet in a hole, drilled through the juxtaposed plates 53, the rivet is first placed on the threaded end 33 of the mandrel 32 while the latter is being rotated by the air motor of the rotary unit in a clockwise direction through the shaft 43. The rivet, while mounted on the mandrel, is thrust into the hole, whereupon the valve 24 of the squeeze tool is opened to introduce air under pressure into the cylinder, actuating its piston 14, thus advancing the cam 15 against the roller 22 of link 21 to exert a forward thrust on plunger 17. The forward end of plunger 17 bears against the lever 48 at its lower end to rock the same on its pivot, thereby reTRACTING the mandrel 32 with a force sufficient to collapse the walls of the rivet 54, creating an annular head 57 therein flush against the inner plate of the work assembly 53 on the "blind" side thereof.

After satisfactorily clinching the rivet 54 in the manner described, the direction of rotation of the mandrel 32 is reversed by actuating the lever 30 on the side of rotary unit housing 25. This action reverses the air motor which drives gears 26 40 and 42 in the opposite direction through shaft 43, causing the mandrel to be driven, by means of pinion 42 in a counter-clockwise direction which retracts the same from the threads of the rivet 54, leaving the latter intact in the work pieces, binding them in fixed relationship.

Manifestly, the construction as shown and described is capable of some modification and such modification as may be construed to fall within the scope and meaning of the appended claims is also considered to be within the spirit and intent of the invention.

What is claimed is:

1. Apparatus for installing hollow, internally threaded rivets including a body having a head provided with an undercut track, a threaded mandrel rotatably and reciprocally mounted on said head to threadedly receive a rivet and having a gear on one end thereof, a carriage slideable on said track for actuating said mandrel, an air motor carried by said body, an extensible shaft operated by said air motor having a gear engaging the gear of said mandrel for rotating said mandrel to engage a rivet, means in said body for retracting said carriage to correspondingly move said motor shaft and mandrel to collapse said rivet in a work piece assembly and means for reversing said air motor to effect threaded withdrawal of said mandrel from the installed rivet.

2. Apparatus for installing hollow, internally threaded rivets including a body having a head, a carriage held against other than longitudinal sliding movement on and exteriorly of said head, an air motor mounted on said head, an extensible shaft operated thereby having a gear thereon, a mandrel rotatably mounted in said head and reciprocated by said carriage, means on said mandrel for receiving and releasably holding a rivet for installation in a work piece assembly, a gear carried by said mandrel engageable with the gear of said motor shaft for rotating said mandrel, means in said body for actuating said carriage for imposing a collapsing force on said rivet by retracting said mandrel and means for reversing the direction of rotation of said air motor to effect withdrawal of the mandrel from the collapsed rivet.

3. Apparatus for installing hollow interiorly threaded rivets including a body having a head,

a carriage slidably disposed on said head, a threaded mandrel rotatably and reciprocally mounted in said head and actuated by said carriage, a gear mounted on one end of said mandrel, a reversible air motor mounted on said body, an extensible shaft actuated by said motor having a gear engaging the gear of said mandrel for rotating said mandrel to receive a rivet, means for retracting said carriage to exert a pull on said mandrel, effective to collapse said rivet intermediate its ends in juxtapositioned work pieces and means for reversing said air motor

to effect withdrawal of said mandrel from an installed rivet.
